UNITED STATES PATENT OFFICE.

OWEN DODGE AND SAMUEL G. CAMP, OF COLORADO SPRINGS, COLORADO; SAID CAMP
ASSIGNOR OF ONE-TWENTIETH TO SAID DODGE.

CHANDELIER.

No. 921,520.

Specification of Letters Patent.

Patented May 11, 1909.

Application filed February 10, 1908. Serial No. 415,145.

To all whom it may concern:

Be it known that we, OWEN DODGE and SAMUEL G. CAMP, citizens of the United States, residing at Colorado Springs, in the 5 county of El Paso, State of Colorado, have invented a new and useful Chandelier, of which the following is a specification.

This invention has reference to improvements in chandeliers, and is designed to provide 10 a combined electric and gas chandelier, with the gas chandelier having a fixed elevation and the electrolier being adjustable as regards its height above the floor.

The present invention is in part an improvement over an adjustable chandelier for 15 which application in the name of myself and Samuel Camp was made for Letters-Patent on April 10, 1907, Serial No. 367,387.

The chandelier of the aforesaid application 20 was designed as an electrolier only and embodies means whereby certain portions of the electrolier are readily adjustable to various heights above the floor. The same features 25 in the main are retained in the chandelier of the present invention, but certain modifications are made in the structure and the chandelier is further modified so as to be used in connection with gas lights in order that either or both kinds of illuminations may be 30 used, as may be desired, or as the exigencies of the case may demand.

In accordance with the present invention there is provided a chandelier through 35 which there are gas passages connected with the gas mains and with which gas passages suitable gas brackets may be connected so as to supply the gas jets with gas without interference with other parts. The gas fixtures are not adjustable with relation to the floor, 40 and combined with these non-adjustable parts are electrical fixtures which may also be non-adjustable, but which may be used without interference with the gas fixture side of the structure. Connected with the gas 45 pipes but without interfering with the functions thereof, is an adjustable member carrying electric fixtures and similar to the like parts shown in the application before mentioned.

50 The invention will be best understood by reference to the following detail description taken in connection with the accompanying drawings forming part of this application, in which drawings—

55 Figure 1 is a longitudinal section, partly

broken away, of the improved chandelier. Fig. 2 is a side elevation of a cam member shown in Fig. 1. Fig. 3 is a detail view of a means of locking the movable parts of the structure in place. Fig. 4 is a central cross 60 section through the lower end of the gas portion of the chandelier, Fig. 5 is a section on the line $y-y$ of Fig. 1 but omitting certain parts. Fig. 6 is a central, longitudinal view of another form of the invention, with parts 65 in elevation, and Fig. 7 is a section on the line $z-z$ of Fig. 6.

Referring to the drawings, there is indicated a ceiling 1 which is shown in a purely conventional manner, and from this ceiling 70 there is indicated the fixed end 2 of the usual gas pipe. Secured upon this pipe is an insulated connection 3 of a common or commercial form used in the installation of gas and electric fixtures but forms no part of the 75 present invention and need not be particularly described.

Screwed into the insulator is the neck 4 of a block 5, which latter may be of cylindrical shape and has an entering passage 6 extending through the neck and then dividing into two other passages 7 leading to the outer walls of the block. Between the passages 6, 7 is a central longitudinal passage 8 formed in the block, and this has a lateral extension 80 9 leading to the walls of the block but having no connection with the passages 6 and 7. The passage 8 is counterbored and adapted to receive the neck 10 of another block 11 through which is a central passage 12 in line 90 with the passage 8. Exterior to the block 5 is the upper end of a pipe 13 of suitable length, secured thereto and carrying at its lower end a support 14 from which project lateral arms 15 connected by annular webs 95 16. The arms 15 have passages 17 terminating in threaded sockets 18 for the reception of suitable gas jet arms, as shown in the drawings or which may be of the ordinary type used in gas chandeliers. 100

The block 11 carries the upper end of another pipe 19 which in turn is connected near its lower end to the lower end of the support 14, and these pipes 13 and 19 are so connected at their two ends as to form a gas tight 105 annular passage between them and into the passages 17. Thus the gas pipe 2 is connected through the insulating coupling 3 to the passages 6 and 7 and by way of the annular passage between the pipes 13 and 19 to the 110

gas pipes screwed into the sockets 18. Exterior to the pipe 13 and secured at its lower end to the support 14, and spaced from the pipe 13 by an annular flange 20 formed on the support 14, is still another pipe 21 which constitutes the exterior member of the chandelier and may be of any ornamental design desired. The upper end of this pipe may abut against the coupling 3 and may be surrounded by a suitable rosette 22 for ornamental purposes.

The webs 16 are each provided at diametrically opposite points with screw sockets 23 into which may be inserted electrolier arms of usual construction, and current is carried to these arms through conductors 24 which are carried up through suitable recesses 25 in the sides of the support 14 exterior to the pipe 13 and between the same and the outer pipe 21 to a point of entrance for the electric conductors adjacent to the passage 9 before referred to, which passage may be coincident with suitable openings, not shown, which may be considered as present in the pipes 13 and 21. Within the pipe 19 there is still another pipe 26, and interior to this last-named pipe is another pipe 27. The pipe 26 may have formed at its lower end an annular flange 28 which is of such size to guide without binding the pipe 27. The upper end of the pipe 27 receives a nut 29, and if need be a clamp nut 30. Below the nut 29 is a washer 31, and below the washer the pipe is surrounded by an elastic ring 32 resting on another washer 33 against which abuts the upper end of the pipe 26. The lower end of the pipe 27 has secured to it a sleeve 34 formed at its lower end with a socket 35 and at its upper end receiving a washer 36.

Surrounding the pipe 27 between the washer 36 and the flange 28 is a hollow cam member 37 having two parallel surfaces 38, 39; which, when the bore 40 of the hollow cam member is concentric with the pipe 27, are at an angle to the longitudinal axis of the pipe. The cam member has still another surface 41, and the distance between the surface 41 and the lower corner 42 of the cam member is greater than the distance between the surfaces 38 and 39 so that when the cam member is so turned by means of a manipulating handle or thumb piece 43 as to bring the surface 38 parallel with the flange 28, and the surface 39 parallel with the washer 36 the washer 36 and the flange 28 are brought into closer relation than when the cam member is turned to bring the surface 41 into engagement with the flange 28 and the edge 42 into engagement with the washer 36. The two pipes 26 and 27 are movable longitudinally with reference to each other by means of the cam member, but when the cam member is so manipulated as to increase the distance between the flange 28 and washer 36 the

washer 31 is brought into closer relation with the washer 33 and consequently the elastic sleeve 32 is compressed and expanded laterally until it is brought into such firm relation with the pipe 19 as to firmly hold the pipes 26 and 27 in any adjusted position with relation to the pipe 19. This provides a means whereby the pipes 26 and 27 may be adjusted to any point desired with relation to the floor. The socket 35 is provided for the purpose of receiving an electric fixture of any desired type, and current is conveyed to this fixture through a conducting cord 44 extending upward through the pipe 27, thence through the passages 12 and 8 into the passage 9, and so to the feeding line. In order that the pipes 26 and 27 may be extended below the gas member of the chandelier, a considerable excess length of the conductor 44 is coiled within the space above the pipe 27 within the pipe 19, as indicated at 45.

In Fig. 6, there is shown a different means for mounting and clamping the tube 26 than that shown in Fig. 1. The lower end of the tube 19 is split longitudinally for a short distance as shown at 45, and between the split lower end of the tube 19 and the outer wall of the tube 26 the ring 32 is located. Surrounding the split lower end of the tube 19 is a split clamp ring 46 having its ends terminating in two opposed parallel wings 47. Hinged to these wings 47 and straddling the same is the forked end 48 of a thumb lever 49. The hinge joint is formed by a through pin 50. The two legs of the fork of the lever 49 are made to approach each other at right angles to the length of the lever so that when the lever is in one position, say the horizontal position, the widest portion of the forked end 48 is coincident with the two wings 47, and the clamp, which is made elastic, springs outward thus releasing the lower end of the tube 19 from pressure and thereby allowing the ring 32 to expand and release the tube 26 to longitudinal movement. When the lever 49 is moved downward toward the tube 26, the contracted portion of the forked end 48 engages the wings 47 and forces them together, thus clamping the ring 46 upon the tube 19 and through it forcing the ring 32 into close engagement with the tube 26 and thereby holding it firmly. The upper end of the tube 26 is swaged so as to be expanded sufficiently to snugly but not tightly fit the interior of the tube 19, thus serving to guide the upper end of the tube 26 in its travel along the tube 19. In Fig. 6 the gas and electric connections have been omitted but will, in practice, be the same as in the structure of Fig. 1.

It is thus apparent that with the improved structure not only may we be enabled to provide the drop electric light with a wide range of movement and safely anchored at any adjusted position, but we are enabled to use the chandelier for the ordinary purposes of a

gas chandelier, and in addition thereto for the ordinary purposes of an electrolier without any interference of one with the other in any respect. Furthermore, the clamping mechanism for locking the adjustable parts in position in no manner interferes with the use of the electric light fixtures and enables us to carry an electric light fixture on the lower end of the adjustable part of the chandelier without affecting the relation of this electric light fixture to the adjustable part of the chandelier when the adjustments are made.

While we have described particular cam structures we are by no means limited to these particular structures but may use other forms of cams for effecting the locking of the movable member of the chandelier. As to the material of the elastic ring 32, this of course will include various known elastic materials such as rubber, or leather, or expandable metallic rings may be used in this construction.

What is claimed is:—

1. A chandelier having two concentric spaced tubes arranged to provide a gas passage between them, which passage leads from a source of supply to gas jets, a longitudinally adjustable member interior to the inner of the two tubes for carrying electric light fixtures and adapted to receive electric conductors housed in said inner tube, an outer tube exterior and in fixed relation to the gas conveying tubes and spaced therefrom and adapted to receive electric conductors in the space thereby inclosed, a block connecting the upper ends of said gas conveying tubes and having a passage to receive gas and to direct the same to the space between said tubes, the outer one of the two tubes forming the closure for the outer ends of the gas passages in said block, the block being also provided with another separate passage adapted to receive an electric conductor leading to the longitudinally adjustable member.

2. A combined electric and gas chandelier comprising a number of concentric spaced tubes or pipes, a block connecting the upper ends of two adjacent tubes and having passages therethrough for conveying gas to the space between the tubes and also having another passage interior to the gas-conveying space for the reception of an electric conductor, a gas fixture support at the lower ends of the gas-conveying tubes, said gas fixture support being provided with means for supporting electric fixtures, electric conductors leading through the space between the gas tubes and a tube exterior thereto and adapted to supply current to the electric fixtures carried by the support at the lower

ends of the gas tubes, and another longitudinally-adjustable set of tubes movable interior to the gas tubes and receiving the conductor entering through the said block, said adjustable tubes being provided with means for receiving electric fixtures and with means for locking the tubes in any position of adjustment.

3. In a chandelier, a number of concentric tubes arranged for the passage of gas and electric conductors, one set of tubes being adjustable longitudinally with relation to the gas tubes, and a clamping means for locking the adjustable tubes in any position of adjustment comprising a laterally-expansible sleeve carried by the adjustable tubes and arranged to engage the inner walls of one of the gas tubes, and a cam mounted loosely on and surrounding one of the adjustable tubes and acting to move the tubes longitudinally with relation one to the other to cause the expansion of the locking sleeve.

4. In a combined gas and electric chandelier, a number of concentric tubular members for the passage of gas and for the housing of electric conductors and a supporting block for the tubular members having a central passage through a portion of its length and diverging for the remainder of the length thereof, and terminating at the outer wall of the block, the outer member of the gas conveying tubular members forming the outer wall of the diverging branches of the gas conveying passage through the block, said block being formed with another passage independent of the gas passage and leading to the interior of the innermost tube of the gas passage.

5. A chandelier having parts longitudinally adjustable and comprising a relatively fixed tube, two other tubes one within the other and having a limited relative movement one to the other and housed in the first-named tube, a laterally-expansible member compressible by longitudinal movement of the two tubes that are relatively movable one to the other, and means for effecting the longitudinal movements of the two relatively-movable tubes comprising a cam member loosely surrounding the smaller of the tubes, said cam member having flat engaging faces arranged at an angle one to the other and perpendicular to diameters of different lengths.

In testimony that we claim the foregoing as our own, we have herto affixed our signatures in the presence of two witnesses.
